V. BENDIX

BRAKE SHOE

Filed Aug. 24, 1925

FIG. 1

FIG. 3

FIG. 2

INVENTOR
VINCENT BENDIX
BY Jn. W. McConkey
ATTORNEY

UNITED STATES PATENT OFFICE.

VINCENT BENDIX, OF CHICAGO, ILLINOIS, ASSIGNOR TO BENDIX BRAKE COMPANY, OF CHICAGO, ILLINOIS, A CORPORATION OF ILLINOIS.

BRAKE SHOE.

Application filed August 24, 1925. Serial No. 51,936.

This invention relates to brake shoes, and is illustrated as embodied in shoes of pressed metal for a three-shoe type brake. An object of the invention is to provide a very strong but inexpensive shoe utilizing abrasive material which may be molded and baked in blocks, or which may be molded in place in a channel formed in the shoe itself.

Having this object in mind, various features relate to forming a channel for the abrasive material by side flanges on cylindrical flanges projecting from a central stiffening rib. Preferably this rib is made by fastening together the flat arcuate web portions of a pair of stampings formed with the desired flanges.

These and other objects and features of the invention will be apparent from the following description of two illustrative embodiments shown in the accompanying drawing, in which:

Fig. 1 is a vertical section through the brake, just inside the wheel, showing the shoes in side elevation;

Fig. 2 is a section through one shoe on the line 2—2, Fig. 1, showing the fastening of the abrasive material in the channel; and

Fig. 3 is a section, corresponding to Fig. 2, through a modified shoe, in which the abrasive material is held by the side flanges.

The brake of Fig. 1 includes a drum 10, and a backing plate 12, inclosing a shoe 14 anchored at 16, a central shoe 18 anchored at 20, and a servo shoe 22 pivoted at 24 to shoe 18. The brake is applied by means such as a cam 26 against the resistance of return springs 28 and 30. Each of the shoes 14 and 22, which may be interchangeable, is forked at its end to form parallel arms straddling the end of shoe 18. Anchor 16 passes through a relatively large opening in shoe 18, and anchor 20 passes through relatively large openings in the parallel arms of shoe 14.

In the form of Figs. 1 and 2, each shoe is formed by fastening together a pair of stampings, the flat arcuate webs 32 of the stampings being fastened together to provide a central stiffening rib. If desired, there may be short reinforcing ribs 34 extending axially at the inner edges of webs 32, while at the outer edges they extend away from each other as cylindrical flanges 36.

At the outer edges of flanges 36 are paral-

lel side flanges 38, forming with the cylindrical flanges 36 a curved channel in which is arranged a block 40 of suitable abrasive material. This block in the arrangement of Fig. 2 is held by threaded bushings 42 in countersunk recesses 44 and engaged by threaded fastenings 46 passing through flanges 36, this construction being specifically claimed in my continuing application No. 263,314, filed March 21, 1928.

In the modification of Fig. 3, side flanges 138, corresponding to side flanges 38, are curved or bent inwardly to provide an undercut channel for the block 140 of abrasive material. If the block is made up and baked in advance, it is formed with grooves in its sides into which the flanges 138 may be spun. I prefer to form the flanges to shape in the first place, and to mold the abrasive material in place as a plastic, baking it afterwards.

While two illustrative embodiments have been described in detail, it is not my intention to limit the scope of the invention to that particular embodiment, or otherwise than by the terms of the appended claims.

I claim:

1. A brake shoe formed of pressed metal formed with a central stiffening rib and with outwardly-extending cylindrical flanges on opposite sides of the rib, and with parallel side flanges on the outer edges of the cylindrical flanges and forming therewith a curved channel, and abrasive material fastened in said channel and projecting therefrom.

2. A brake shoe formed of pressed metal formed with two arcuate flat webs forming a central stiffening rib and with outwardly-extending cylindrical flanges on opposite sides of the rib, each flange integral with one of the webs, and with parallel side flanges on the outer edges of the cylindrical flanges and forming therewith a curved channel, and abrasive material fastened in said channel and projecting therefrom.

3. A brake shoe formed of two stampings, each arranged to provide a flat arcuate web with a cylindrical flange at the outer edge, the stampings being arranged back to back with the webs fastened together and with the cylindrical flanges extending axially in opposite directions, and with parallel side flanges on the outer edges of the cylindrical flanges and forming therewith a

curved channel, and abrasive material fastened in said channel and projecting therefrom.

4. A brake shoe formed of two stampings, each generally channel-shaped in cross-section to provide a flat arcuate web with a projecting stiffening flange at the inner edge and with a cylindrical flange at the outer edge, the stampings being arranged back to back with the webs fastened together and with the cylindrical flanges extending axially in opposite directions, and with parallel side flanges on the outer edges of the cylindrical flanges and forming therewith a curved channel, and abrasive material fastened in said channel and projecting therefrom.

5. A brake shoe having a central stiffen-

ing rib with cylindrical flanges projecting in opposite directions and having at their outer edges inwardly-turned side flanges forming with the cylindrical flanges an undercut channel, and abrasive material held by the side flanges and projecting from the channel.

6. A brake shoe including a metallic backing and friction material thereon, the metallic backing including two separately-formed stampings secured together to form a T section shoe, and having integral portions displaced into the body of the friction material to hold it.

In testimony whereof I have hereunto signed my name.

VINCENT BENDIX.
